DES. 2139

Franklin Simmon, of Washington, D.C.

ass. to

Wm. Miller, of Providence, R.I.

Letters Patent No. 2139-Dated July 18, 1865.

Design for a medallion of Abraham Lincoln.

The schedule referred to in these Letters Patent and making part of the same.

To all whom it may concern:

Be it known that C. Franklin Simmon, of the City of Washington D.C. have originated and produced a new model of which the accompanying photograph is a true representation.

What I claim as my invention or production and desire to secure by Letters Patent is, The design for my gold or silver medallion Portrait of Abraham Lincoln, represented by the photograph herewith attached.
